N. MENDAL SHAFFER, OF NEW YORK, N. Y.

Letters Patent No. 82,999, dated October 13, 1868.

IMPROVED WASHING-MACHINE.

The Schedule referred to in these Letters Patent and making part of the same.

To all whom it may concern:

Be it known that I, N. MENDAL SHAFFER, of the city of New York, county and State of New York, have invented a new and useful Machine for Washing; and I do hereby declare that the following is a full and exact description thereof, reference being had to the accompanying drawings, and to the letters of reference marked thereon, making a part of the specification.

The nature of my invention consists in combining with those washing-machines in which a pump is used to force water through the clothes a perforated pounder or squeezer, constructed of wire or otherwise, which acts reciprocatingly with the pump-boxes, and serves to keep the clothes in place while the water is forced through them, as is hereinafter described.

Figure 1 is a side view of the machine, showing its internal structure.

Figure 2 is a top view of the same.

A A is a lever, pivoting at O, with movable joints at C C.

B is a movable wire box, a top view of which is given at M in fig. 2.

E is a movable piston, with valve, which forces the water through the tube H, with stationary box D, with valve at the bottom, forming a pump which compels the water to form a circuit in the direction indicated by the arrows; so that the same water is used

over until it has done the work, or needs to be changed for clean water.

L is a stationary wire box.

P is open space between, which forms the clothes-box.

X is a box, around which the water flows which is put in, to give the machine proper proportions, and to accommodate the necessary machinery.

The operation of washing is performed by placing the clothes in the box P, and putting in enough water or suds to form a circuit and work the lever till they are clean. The piston-rod attached to B should be regulated or lengthened according to the amount of clothes in the box.

I do not desire to claim as my invention the washing-machine when composed of the pump and box L, except when in combination with the wire box B; but

What I do desire to claim as new, and protect by Letters Patent, is—

The method of squeezing the suds through the clothes, by means of unresisting wire boxes B and L, or their equivalent, in combination with the pump H E and D, as herein described and set forth.

N. MENDAL SHAFFER.
